UNITED STATES PATENT OFFICE.

GEORGE A. SEIB, OF ILION, NEW YORK, ASSIGNOR TO REMINGTON TYPEWRITER COMPANY, OF ILION, NEW YORK, A CORPORATION OF NEW YORK.

TYPE-WRITING MACHINE.

1,153,716.

Specification of Letters Patent. Patented Sept. 14, 1915.

Original application filed February 11, 1913, Serial No. 734,091. Divided and this application filed February 12, 1914. Serial No. 818,232.

To all whom it may concern:

Be it known that I, GEORGE A. SEIB, citizen of the United States, and resident of Ilion, in the county of Herkimer and State of New York, have invented certain new and useful Improvements in Type-Writing Machines, of which the following is a specification.

My invention relates, generally speaking, 10 to typewriting machines, the invention being directed more particularly to tabulating mechanism embodied in such machines.

The objects of the invention will appear from the following description, the invention 15 consisting in the features of construction, arrangements of parts and combinations of devices to be hereinafter set forth and particularly pointed out in the appended claims.

20 In the accompanying drawings wherein like reference characters indicate corresponding parts in the various views, Figure 1 is a fragmentary side elevation with parts in section of one form of typewriting machine embodying my invention, only so much of the machine being shown as is necessary to arrive at an understanding of the invention. Fig. 2 is a fragmentary plan view of the same. Fig. 3 is a fragmentary detail 25 side elevation of a portion of the structure, the view showing the parts as they appear when one of the column selecting keys is depressed and the carriage is released. Fig. 4 is a fragmentary detail side view on an enlarged scale and partly in section of one 30 of the column selecting stops and some of the associated parts. Figs. 5 and 6 are fragmentary detail perspective views of portions of the line lock mechanism.

35 While I have shown my invention in the present instance embodied in a No. 11 Remington machine it should be understood that the invention may be embodied in various styles of typewriting machines.

40 The present case is a division of my application Serial No. 734,091, filed February 11th, 1913.

45 The frame of the machine comprises a base 1, corner posts 2 and a top plate 3. A 50 rectangular carriage comprises end bars 4, a forward cross bar 5 and a rear cross bar 6. The forward and rear cross bars are grooved to receive anti-friction balls or rollers 7 which are likewise received in fixed guide

rails 8 secured to the top plate of the machine. A cylindrical platen 9 is supported by the carriage in the usual manner. Upwardly and rearwardly swinging type bars 10 are adapted to strike against the front face of the platen. These type bars are 55 pivoted at 11 to the usual type bar hangers and have a segmental arrangement. Each type bar is actuated from a printing key 12 through the usual train of connections comprising links 14 and 15 and an intermediate 60 sub-lever 16, which latter is pivoted on a hanger 17. Each of the links 14 is connected to a key lever 18 fulcrumed at its rear end on a fulcrum plate 19. A returning spring 20 is connected at one end to a key lever 70 and at its opposite end to a supporting plate 21 secured to the base 1 of the machine. A universal bar 22 extends beneath the key levers and is connected in the usual manner (not shown) with the dog rocker which carries a feed dog. This feed dog co-operates with a double escapement wheel 23 secured to an escapement wheel shaft 24 adapted to turn in a bearing 25 fixed to the top plate of the machine. The forward end of the escapement wheel shaft has a feed pinion 26 secured thereto. A feed rack 27 meshes with the feed pinion 26 and is carried by arms 28 pivoted by shouldered pivot screws 29 to upwardly extending lugs 30 which project 75 from the rear cross bar 6 of the carriage. A leaf spring 31 is secured by screws 32 to the cross bar 6 of the carriage and bears at its free end on the top of the feed rack 27 to force the latter into mesh with the feed 80 pinion. The carriage is thus mounted for movement from side to side of the machine over the top plate, the carriage being propelled from right to left by a spring drum 33 connected by a band 34 with an arm 35 85 secured to the carriage. It should be understood that the movement of the carriage from right to left is resisted by the usual escapement mechanism.

90 The parts thus far described constitute 100 part of the ordinary equipment of the No. 11 Remington machine.

95 The tabulator mechanism in the present instance includes the ordinary denominational stop mechanism employed in the No. 105 11 Remington machine and which comprises a series of push rods 61 each provided at its forward end with a key 62. These rods ex-

tend through guide openings in a depending member 63 secured to the base of the machine by screws 64. The rear end of each push rod is pivoted, as at 65, to an upwardly extending denominational stop lever 66. The levers 66 are pivoted at 67 in a tabulator frame 68 which is secured to the frame of the machine in the usual manner. The stop levers 66 extend forwardly at their upper ends to provide denominational stops 69 which extend through guide openings in a guide comb or plate 70 secured to the tabulator frame. Each push rod 61 is returned to the normal position by a contractile spring 71 secured at one end to a sleeve 72 fastened to the associated push rod and at its opposite end to the member 63. A slotted universal releasing bar 73 receives in the slots thereof the push rods 61 and each rod has fixed thereon a sleeve 61^a to engage and actuate the bar. This universal bar is in the nature of an angle-iron which is secured by screws 74 to a cross bar 75 which is formed in one piece with upwardly extending arms 76 supported on a pivot rod 77. Each of the arms 76 is provided with a rearwardly off-set ear 78 which is pivotally connected with a rearwardly extending link 79. The rear end of each link 79 is pivoted as at 80 to a depending crank arm 81 fixed to a rock shaft 82 mounted at its ends in the base of the machine. Another depending crank arm 83 is fixed to the rock shaft and has one end of a contractile spring 84 connected thereto, the opposite end of said spring being connected to a depending pin 85 secured to the base of the machine. It should be understood that the arm 83, spring 84 and pin 85 are situated to one side of the series of key levers 18. A crank arm 86 is secured to the rock shaft 82 and extends downwardly and forwardly therefrom and then upwardly and rearwardly where pivotal connection is made, as at 87, with an upwardly extending link 88 which in turn is pivoted at 89 to a carriage releasing device or lever 90. This releasing device is pivoted at 91 to a bracket 92 secured to the top plate of the machine and a shoe 93 at one end of the lever or releasing device extends beneath the feed rack 27 and is adapted to elevate the feed rack against the pressure of its spring 31 when a denominational key 62 is actuated. The carriage has rearwardly extending bracket arms 94 secured thereto by screws 95. The rear ends of these bracket arms are connected to a column stop bar 96 provided with teeth 97 on the upper and lower edges thereof. Column stops 98 are received in the interdental spaces between the teeth 97 to secure the column stops in the different positions to which they may be adjusted along the column stop bar. It will be understood that an actuation of a denominational key 62 is effective to project the corresponding denominational stop 69 into the path of the column stops 98. At the same time the universal bar 73 is moved rearwardly, thus effecting an actuation of the rock shaft 82 which controls the releasing device 90, thereby lifting the feed rack out of engagement with the feed pinion 26 to release the rack from control of its escapement mechanism. This denominational tabulating mechanism is the same, or essentially the same, as that embodied in the No. 11 Remington machine. In the present instance I have provided column selecting mechanism which may be used in conjunction with the denominational tabulator mechanism hereinbefore described. Thus I have provided rearwardly extending bracket arms 99 which are secured by screws 100 to a scale bar 101 of the carriage. The rear ends of these bracket arms 99 are apertured to receive the reduced ends of a pivot rod 102, which rod is fixedly secured to the bracket arms by screws 103. This pivot rod extends substantially throughout the length of the carriage and parallel with the axis of the platen and is provided with a series of teeth 104 which are on the under side only thereof. These teeth are spaced at letter space intervals throughout, or substantially throughout, the length of the pivot rod. A series of column selecting stops, each of which is designated as a whole by the reference numeral 105, is pivotally mounted on the pivot rod 102. Each of these column selecting stops in the present instance comprises the lever which extends fore and aft of the machine and is provided at its forward end with a finger key 106. The rear end of the lever is provided with a bearing opening by which it may be received on the pivot rod. An off-set pin or contact portion 107 projects from the left-hand side of each lever for engagement with a co-operative stop 108 on the frame of the machine, as will hereinafter more clearly appear. Each column selecting stop is provided with a spring-pressed latch 109 (see Fig. 4), the stem of which is adapted to move in a bearing opening 110 in the body portion of the stop 105. The lower end of the latch is bent at right angles to the stem to provide an engaging member 111 co-operative with the teeth 104 on the pivot rod 102. An expansion spring 112 surrounds the stem 109 of the latch and is received in an opening 113 in the body portion of the stop lever. The lower end of the spring 112 bears against the bottom wall of this opening and the upper end of the spring bears against a head or finger piece 114 which is connected to the stem of the latch by a threaded connection 115. The power of the spring 112 is exerted against the latch to normally maintain it in engagement with the teeth 104. The power of this spring is also to

5 maintain the corresponding stop lever 105 against movement from the normal position and to return the stop lever to such normal position when the stop lever is turned on the pivot rod 102. In order to facilitate such 10 return movement without unduly increasing the size of the spring 112 I prefer to employ an auxiliary spring returning means which is clearly illustrated in Fig. 4. Thus 15 the rear side of the pivot rod 102 is provided with a recessed or flattened face 116 against which a spring-pressed plunger 117, also provided with a flat contact face, is adapted to engage. This plunger is received 20 in an opening 118 formed in the body portion of the stop lever, and a coiled expansion spring 119 surrounds a guide pin or stem 120 which projects from the head 117 and works in a central opening 121 in a screw 25 122 received in a tapped portion of the opening 118. This screw may be provided with a nick 123 for a screw driver or suitable tool by which the screw may be threaded into or withdrawn from the tapped opening 30 in which it is received. The spring 119 bears at one end against the screw 122 and at its opposite end against the head 117 of the plunger so as to force the plunger into contact with the flattened portion 116 of the 35 pivot rod, thus exerting a force to retain the associated stop lever 105 in its normal position and to return it to such normal position when pressure on the depressed finger key of such stop lever is removed. It will be understood, therefore, that the spring 119 augments the action of the spring 112 which is likewise effective for the same purpose.

40 It will be seen that each stop lever 105 may be turned on its pivot rod from the normal position shown in full lines in Fig. 2 rearwardly to the dotted line position represented in Fig. 2; that when the stop lever is turned to the dotted line position the key 106 which is carried thereby may be brought 45 into contact with a work sheet A in the machine and that the left-hand edge of the key may be brought into register with an indicating mark, such as a line 124, which divides two adjacent vertical columns *a*, *b*, *c*, *d*, *e* and *f* on the work sheet; that this 50 same turning movement of the column selecting stop from the full to the dotted line position represented in Fig. 2 is effective to disengage the latch 109 from the pivot rod 55 and to move the said latch and the plunger 117 to such positions relatively to the pivot rod that they no longer tend to return the stop to normal position around the pivot rod; and that when the stop is so positioned 60 the latch is maintained disengaged from the teeth 104 so that a stop at this time is free to be adjusted to the desired position along the pivot rod 102. When, however, the stop 65 is again moved from the dotted line position shown in Fig. 2 to the full line position

of this same stop, the latch 109 will again be brought into engagement with the teeth 104 on the pivot rod to secure the stop against movement along the rod and in the position to which it has been adjusted longitudinally of the rod. Nevertheless, at this time the stop 105, or any of them, maintained in the normal position, is free to be depressed by its finger key, as represented in Fig. 3, without disengaging the spring 75 pressed latch from the teeth 104.

70 A universal release bail or bar 125 extends throughout the length of the carriage beneath the stop levers 105 and in the path of movement of the latter when they are 80 depressed from the normal position. This bar is flattened and turned rearwardly at the ends thereof, as indicated at 126, the rearwardly extending portions of the bar extending beneath the usual carriage release 85 keys 127 to which the release bar is fixedly secured by screws 128. Each release key is formed as a part of a release lever 127^a which is pivoted on a shouldered screw 128^a and is held in place thereon by a nut. The 90 forward portion of each lever 127^a is slotted as at 129 to receive a shouldered screw 129^a, so as to enable the release levers 127^a to move independently of the screws 129^a. A nut is received on the outer end of each 95 shouldered screw 129^a. The rear end of each release lever extends beneath the feed rack 100 27 so that a depression of either release key 127 or the universal release bar 125 is effective to lift the rack out of engagement 100 with the feed pinion 26, as shown in Fig. 3, thus freeing the carriage for movement from right to left under the power of its spring drum.

105 The stop 108 on the frame of the machine is the same stop which is ordinarily employed in the No. 11 Remington machine to actuate the line lock mechanism and the means by which this stop is rendered effective to control the operation of the universal locking bar are the same as those ordinarily employed in such machine. Thus the stop 108 is pivoted and is also adapted to receive a slight movement from right to left with the carriage and in this movement is effective to throw a universal locking bar 110 into the path of engaging hooks on the key levers 18 to prevent an actuation of said key levers. This will be better understood from an inspection of Figs. 2, 5 and 6 from 115 which it will be observed that a slide or plate 130 is provided with slots 131 which receive headed screws 132 by which the plate is supported to receive a limited longitudinal movement, the screws 132 being received at their threaded ends in tapped openings in the under side of the forward fixed carriage rail 8. A three-arm lever 133 is pivoted at 134 to the slide 130, one arm 120 of this lever being connected to one end of 125

- a contractile spring 135 which has its opposite end connected to a pin 136 on a carriage pointer 137. A second arm of this lever 133 has a finger 138 which is received in a slot 139 in the slide 130. The third arm of the lever 133 is bent forwardly at the end thereof to form a contact finger 140 which extends into the path of a depending arm on the stop 108. It will be seen therefore that
- 5 a movement of the stop 108 from right to left is effective to transmit a bodily movement to the lever 133 and slide 130 on which it is mounted, this movement of the parts being effected against the pull of the spring
- 10 135. The left-hand end of the slide 130 is bent downwardly to form a depending finger 141 which is received in a cut-out or slot 142 in an angular lever 143. This lever is pivoted at 144 and has its opposite arm
- 15 pivotally connected at 145 to a depending link 146 which in turn is pivoted at its lower end, as at 147 (Fig. 1) to a universal locking bar 148. This bar has a flange 149 which is adapted to be received beneath the hook-
- 20 like engaging members 150 on the key levers 18. The locking bar is pivoted to the base of the machine on pivots 151 so that when the stop 108 is moved to the left motion is transmitted to the locking bar 148 through
- 25 the intermediate connections 146, 148, 130 and 133 to move the locking bar to the operative position where it prevents an effective depression or printing movement of any of the key levers. It will be understood,
- 30 35 therefore, that when one of the column selecting keys 106 is depressed this results in releasing the carriage, and the carriage will move to the left under the power of its spring drum until the contact pin 107 on the depressed stop engages the stop 108 on the frame of the machine. The stop 108 will be moved a short distance to the left before the carriage is arrested, thus actuating the line lock mechanism to prevent an operation
- 40 45 of the printing keys until the depressed column selecting key has been released and the parts restored to normal position. The release of pressure on the column selecting key enables the actuated column selecting
- 50 55 stop to return to normal position, thereby releasing the stop 108 when the spring 135 will return the stop 108 to normal position and will release the line lock mechanism controlled thereby. It will be seen, therefore, that a printing operation cannot be effected until the column selecting key and the parts controlled by a depression thereof have all been restored to normal position.
- 60 From an inspection of Fig. 2 it will be observed that each of the column selecting keys has indices inscribed thereon which correspond to the headings of the corresponding column which it is operative to select.
- 65 For example, there are shown in the present instance, six columns *a*, *b*, *c*, *d*, *e* and *f* on
- the blank A and there are six column selecting stops and keys, each key head bearing an inscription which corresponds to the heading at the top of the particular column which the key in question is operative to 70 select. Thus the first column having the heading "Total", the first key counting from the left has a corresponding designation thereon. By these means it is unnecessary for the operator to bear in mind the 75 location of the particular column in which an item is to appear. If, for example, the first item to be written in a line is to appear under the heading "Parts", it is merely necessary for the operator to actuate the 80 key bearing the corresponding designation "Parts" in order to select the proper column.
- 85 The adjustment of the column selecting stops longitudinally of the pivot rod 102 enables the operator to readily adjust said stops according to the location of the columns where the items are to appear and by swinging a column selecting stop rearwardly to the dotted line position and bringing about a registration between the left-hand edge of the key and the left-hand dividing line for the corresponding column, the stop can be accurately set according to the sheet in the machine. After the column 90 95 selecting stops have been adjusted in the manner described the column stops 98 will receive an adjustment in accordance with the adjustment of the column selecting stops. When the different stops have been adjusted 100 as stated they will appear as shown, for example, in Fig. 2. A depression of a column selecting key at this time will effect a release of the carriage and will arrest the carriage through the coöperation of the depressed column selecting stop with the stop 108 on the frame of the machine. If, for example, the third column selecting key bearing the inscription "Parts" be depressed the carriage will be released and arrested 105 through the coöperation of the third column selecting stop, counting from the left, with the stop 108, the first two column selecting stops being skipped. This is effective to arrest the carriage in the columnar field *c* indicated by the heading "Parts". A denominational key is then actuated in accordance with the number to be written and a number, up to one including six digits, in the present example, may be written in the 110 115 properly selected columnar field. The next or any succeeding column may then be selected as before, and a denominational key actuated as previously described to secure a proper denominational positioning of the carriage to begin the number to be written in the appropriate column.
- 120 125 While I have shown the column selecting mechanism of my invention embodied in a No. 11 Remington machine, it will be under- 130

stood that it may be embodied in the manner herein shown and described in a No. 10 Remington machine. In this event the fixed number of columns that may be selected by 5 the ordinary column selecting mechanism of the No. 10 machine may be added to indefinitely by the use, in conjunction therewith, of the column selecting mechanism herein shown and described.

10 By removing the rod 102 any desired number of key carrying column selecting stops may be placed on the rod and the rod readily replaced. I have shown the employment of six of such stops in the present instance merely by way of example, this being all that is required for blanks of the character indicated but this number may be varied at will.

It will be seen that by my present invention the column selecting stops are separate and independently adjustable; that the column selecting mechanism may be used merely as such independently of the denominational selecting mechanism or may be 25 used in conjunction therewith to first select a columnar field and then effect a proper selection of the denominational position within that columnar field, or may be used in conjunction with the column selecting mechanism of the No. 10 Remington machine. On the other hand, the denominational mechanism herein shown may be used alone for the selection of denominational positions within succeeding columnar fields 30 determined by the positions of the column stops 98; or the denominational mechanism as hereinbefore described may be used in conjunction with the column selecting mechanism. It will be understood, therefore, 35 that the construction of my present invention is adapted to a wide range of uses and the tabulating mechanism as a whole is operative differently under varying conditions of use. Moreover, it will be understood that 40 45 the invention may be readily embodied in existing forms of typewriting machines, such, for example, as the No. 10 Remington machine or the No. 11 Remington machine without modifying, or materially modifying, the structural features of such machines as they now exist and that the column selecting mechanism is simple in construction and effective in operation.

Various changes may be made without departing from the spirit and scope of my invention.

What I claim as new and desire to secure by Letters Patent, is:—

1. In a typewriting machine, the combination of a carriage, a series of pivoted key controlled column selecting stops carried directly thereby and independently movable to operative position, said column selecting stops being relatively adjustable to different column selecting positions, and a coöperative

stop with which said key controlled column selecting stops co-act when they are moved to operative position.

2. In a typewriting machine, the combination of a carriage, a series of key controlled column selecting stops pivoted directly on the carriage and independently movable to operative position, said column selecting stops being relatively adjustable to different column selecting positions, a coöperative stop with which said key controlled column selecting stops co-act when they are moved to operative position, and carriage release mechanism actuated to release the carriage by a movement of any of said column selecting stops to operative position.

3. In a typewriting machine, the combination of a carriage, a series of spring-returned key-carrying pivoted column-selecting stops carried directly by the carriage and independently movable into and out of operative position, means for affording a relative adjustment between said stops to different column determining positions and for holding the stops against relative movement toward and away from each other in the column determining positions to which they may be adjusted without affecting the operativeness of said stops to move into and out of operative position, and a coöperating stop carried by the frame of the machine.

4. In a typewriting machine, the combination of a carriage, and tabulator mechanism including a pivot rod, a key actuated tabulator stop which receives a pivotal movement on said pivot rod into and out of operative position, co-acting locking means on the stop and rod for locking the stop against movement along the rod when the stop is turned to one position on the rod and for freeing the stop for adjustment along the rod when the stop is turned to another position, and a coöperative stop with which the key actuated stop is adapted to be brought into coöperative relation, the key actuated stop being movable into and out of coöperative relation with said coöperative stop without releasing the key actuated stop from its locking means.

5. In a typewriting machine, the combination of a carriage and tabulator mechanism including a pivot rod having teeth on only one side thereof, a tabulator stop mounted to turn on said pivot rod, and a spring pressed latch carried by and movable relatively to said stop and which engages the teeth of said pivot rod when the stop is turned to one position, thereby locking the stop against movement along the rod and which latch is automatically freed from said teeth when the stop is turned to another position so that the stop may be adjusted along the rod.

6. In a typewriting machine, the combination of a carriage, and tabulator mechanism

- including a pivot rod, a stop pivoted on and adjustable along said rod, and means including a spring-pressed device for locking the stop against movement along the rod and also operative to return the stop to normal position around said pivot rod. 70
7. In a typewriting machine, the combination of a carriage, a tabulator stop, a series of key carrying stops independently movable under the control of the keys thereon into and out of coöperative relation with said tabulator stop, a pivot rod on which said key carrying stops are mounted and receive a pivotal movement into and out of coöperative relation with said tabulator stop and which are adapted to be relatively adjusted to different positions along said pivot rod, and locking means for locking each of said stops against movement along said rod, said locking means comprising a spring pressed latch on each key carrying stop operative to lock the stop against movement along the rod. 75
8. In a typewriting machine, the combination of a carriage, and tabulator mechanism including a key controlled adjustable stop that is adapted to be moved from its normal position into coöperation with a work sheet in the machine to aid in adjusting the stop with reference to the work sheet. 80
9. In a typewriting machine, the combination of a carriage, and tabulator mechanism including a key controlled stop carried by the carriage and adjustable thereon in the direction of the travel of the carriage, said stop being movable from its normal position into coöperation with a work sheet in the machine to aid in adjusting the stop with reference to the sheet and widthwise thereof. 85
10. In a typewriting machine, the combination of a carriage, and tabulator mechanism including a series of independently operable key-carrying tabulator stops carried by the carriage and relatively adjustable in the direction of the travel of the carriage, each of said stops being movable from its normal position into coöperation with a work sheet in the machine to aid in adjusting the stops with reference to the sheet and widthwise thereof. 90
11. In a typewriting machine, the combination of a carriage, and tabulator mechanism including a series of independently operable key-carrying tabulator stops carried by the carriage and relatively adjustable in the direction of the travel of the carriage, each of said stops being movable from its normal position into coöperation with a work sheet in the machine to aid in adjusting the stops with reference to the sheet and widthwise thereof, and means for locking said stops against adjustment when they are in the normal position and for freeing the stops from said locking means when the stops are moved into coöperation with the paper. 95
12. In a typewriting machine, the combination of a carriage, and tabulator mechanism including a pivoted key-carrying tabulator stop movable by its key into and out of operative position and adjustable in the direction of the travel of the carriage, said stop being movable on its pivot from the normal position to bring the key on said stop into coöperation with a work sheet in the machine to aid in adjusting said stop relatively to the sheet. 100
13. In a typewriting machine, the combination of a carriage, a fixed pivot rod carried by the carriage at the front portion thereof, a series of key carrying tabulator stops pivoted on said pivot rod, a coöperative stop on the frame of the machine with which said key carrying stops are adapted to be brought into coöperative relation by a pivotal movement thereof, spring means for returning said key carrying stops to normal position out of coöperative relation with said coöperative stop, and means for affording a relative adjustment between said key carrying stops along said pivot rod. 105
14. In a typewriting machine, the combination of a carriage, and tabulator mechanism comprising a series of key controlled column selecting stops, the key for each stop being inscribed to correspond to the heading of one of the columns of a work sheet to be used in the machine, and means by which each column stop and its key may be adjusted according to the position of the column on the work sheet to be selected thereby. 110
15. In a typewriting machine, the combination of a carriage, a series of key carrying stop levers carried by the carriage and extending fore and aft of the machine, means for affording an adjustment of said levers relative to each other and in the direction of the travel of the carriage, and a universal release bar actuated by said levers and operative to free the carriage from control of its escapement mechanism. 115
16. In a typewriting machine, the combination of a carriage, a stop carried by the frame of the machine, a series of independently operable key controlled column selecting stops carried by the carriage and each movable by its key independently of the others into coöperative relation with said first mentioned stop, carriage releasing means controlled by an actuation of each of said key controlled column selecting stops to release the carriage, printing instrumentalities, and means controlled by said first mentioned stop for locking said printing instrumentalities against actuation. 120
17. In a typewriting machine, the combination of a carriage, a series of key controlled column selecting stops carried thereby and independently movable to operative position, said column selecting stops being 125
- 130

relatively adjustable to different column selecting positions, a coöperative stop with which said key controlled column selecting stops co-act when they are moved to operative position, printing instrumentalities, and means controlled by said coöperative stop for locking the printing instrumentalities against actuation.

18. In a typewriting machine, the combination of a carriage, a series of spring-returned key-carrying column-selecting stops carried by the carriage and independently movable into and out of operative position, means for affording a relative adjustment 10 between said stops to different column determining positions and for holding the stops against relative movement toward and away from each other in the column determining positions to which they may be 15 adjusted without affecting the operativeness of said stops to move into and out of operative position, a coöperating stop carried by the frame of the machine, printing instrumentalities, and means controlled by said 20 25 coöperative stop for locking the printing instrumentalities against actuation.

19. In a typewriting machine, the combination of a carriage; and tabulator mechanism including a pivot rod, a key actuated 30 tabulator stop which receives a pivotal movement on said pivot rod into and out of operative position, co-acting releasable locking means on the stop and rod for locking the stop against movement along the rod 35 and for freeing the stop for adjustment.

Copies of this patent may be obtained for five cents each, by addressing the "Commissioner of Patents,
Washington, D. C."

along the rod, a coöperative stop with which the key actuated stop is adapted to be brought into coöperative relation, the key actuated stop being movable into and out of coöperative relation with said coöperative 40 stop without releasing the key actuated stop from its locking means, printing instrumentalities, and means controlled by said coöperative stop for locking the printing instrumentalities against actuation.

20. In a typewriting machine, the combination of a carriage, a fixed pivot rod carried by the carriage at the front portion thereof, a series of key-carrying tabulator stops pivoted on said pivot rod, a coöperative stop on the frame of the machine with which said key carrying stops are adapted to be brought into coöperative relation by a pivotal movement thereof, spring means for returning said key carrying stops to 55 normal position out of coöperative relation with said coöperative stop, means for affording a relative adjustment between said key carrying stops along said pivot rod, printing instrumentalities, and means controlled 60 by said coöperative stop for locking the printing instrumentalities against actuation.

Signed at Ilion, in the county of Herkimer, and State of New York this 9th day of February, A. D. 1914.

GEORGE A. SEIB.
